ULTRA-HIGH FREQUENCY HETERODYNE RECEIVER CONTAINING TANK CIRCUIT ARRANGEMENT

Wolf Dietrich Gosselau, Dusseldorf, Germany, assignor to
North American Philips Company, Inc., New York,
N.Y., a corporation of Delaware

Filed June 28, 1960, Ser. No. 39,383

Claims priority, application Germany Aug. 8, 1959

5 Claims. (Cl. 325—436)

The invention relates to an ultra-high frequency heterodyne receiver including a tank circuit arrangement comprising two inductively and/or capacitively coupled band-pass filter resonant circuits to which a preferably self-oscillating mixer stage is inductively coupled, for example through a conductor loop connected in parallel with the inner conductor of the second band-pass filter circuit.

Such receivers have a limitation in that the maximum value of the oscillator oscillations appearing in the mixer stage, which have a comparatively large amplitude and are closely adjacent the input oscillations in frequency, must be limited at the input of the band-pass filter and of the antenna in order to prevent them from interfering with receivers in the vicinity. In spite of careful design of the arrangement and even when several known steps are taken with respect to screening and neutralisation, it has been found that oscillator voltages always reach the antenna input and partly also the outer surface of the housing of the heterodyne portion so that there is considerable radiation.

In an ultra-high frequency heterodyne receiver of the kind described, these limitations can be eliminated if, in accordance with the invention, between the part of the coupling loop connected to the mixer stage and an adjacent part of the said inner conductor at which the potential of the input oscillations is a maximum, a small capacitor is connected of a value such that at the input of the band-pass filter the oscillations at oscillator frequency are at least substantially compensated.

The invention will now be described more fully, by way of example, with reference to the drawing which shows the heterodyne portion.

The heterodyne portion 1 comprises four chambers 1a, 1b, 1c and 1d designed as resonant circuits which may be tunable. The input oscillations are supplied by an antenna to an input circuit (not shown) which is arranged in the first chamber 1a and controls an electron tube 2 in known manner through the cathode of this tube. The grid of this triode 2 is connected to the wall between the chambers 1a and 1b. The direct-current supply conductors for this valve and for a mixer tube 3 connected between the chambers 1c and 1d are conventional and not shown for the sake of clarity.

The anode of the tube 2 is connected through a capacitor C_1 to an inner conductor L_1 of the second chamber 1b to couple the input oscillations to the chamber 1b. The conductor L_1 is connected near its ends through trimmer capacitors T_1 and T_2 to the wall between the chambers 1a and 1b. The other end of the conductor L_1 is connected through a variable capacitor C_3 , for example a rotary capacitor, to the outer wall at the end face of the chamber 1b so that the resulting resonant circuit can be tuned by variation of the capacitor C_3 .

The next chamber 1c contains an inner conductor L_2 which is connected through trimmer capacitors T_3 and T_4 to the wall between the chambers 1b and 1c. The lower end of this conductor is connected through a variable tuning capacitor C_4 to the end face of the chamber wall 1c. A coupling loop K is provided on either side of the wall between the chambers 1b and 1c to couple the input oscillations from chamber 1b to chamber 1c. The upper part of loop K is conductively connected to the

2

wall while its lower part is passed through an aperture in the wall in an insulating manner. The upper end of the conductor L_2 is connected through a capacitor C_2 to the wall between the chambers $1b$ and $1c$ also.

5 In the wall between the chambers $1c$ and $1d$ provision
 is made of a self-oscillating mixer tube 3 the grid of
 which is conductively connected to this wall. Its cath-
 ode is connected to a conductor loop L_M to couple the
 input oscillations to the tube 3 . The larger part of loop
 $10 L_M$ extends parallel to the inner conductor L_2 of this
 tank circuit while the other end of the loop L_M is con-
 nected through a capacitor C_5 and a resistor R to the
 wall between the chambers $1c$ and $1d$.

15 The anode of the valve 3 is connected through a capacitor C_7 to an inner conductor L_3 in the chamber 1d to effect the generation of local oscillations of a frequency determined by the chamber 1d. This inner conductor is connected through trimmer capacitors T_5 and T_6 to the outer wall and through a variable tuning capacitor C_6 to 20 one end face. One of the intermediate frequencies produced can be taken through a high-frequency choke coil D from the capacitor C_7 .

25 By means of the circuit components shown, particularly the trimmer capacitors and an auxiliary coupling coil L_K connected between the conductors L_1 and L_2 and, if required, by apertures in at least one of the walls, the known circuit arrangement described so far can be designed so as they have a certain band-pass characteristic. Particularly, the input circuit in the chamber $1a$ 30 and the band-pass filter in the chambers $1b$ and $1c$ may be designed to have desired band-pass characteristics so that tuning of the oscillator circuit in the chamber $1d$ enables the reception of signals in the desired range of, say, from 470 to 800 mc./s., as may be required for television reception in the ultra-high frequency range. By adjustment of the separate coupling members, it can further be ensured that the oscillator amplitude at the self-oscillating mixer stage including the valve 3 is substantially 35 constant and that a satisfactory conversion gain is obtained throughout the entire range.

40 taken throughout the entire range. In known circuit arrangements of this kind, however, the oscillator oscillations were transmitted in a considerable degree by the chamber 1d to the circuits in the chambers 1b and 1a and thus to the antenna. According
 45 to the invention, this is avoided by the provision of a small compensating capacitor C_u of, for example, 2 pf. between the cathode of the valve 3 and the end of the inner conductor L_2 of the secondary circuit of the band-pass filter in the chamber 1c not connected to the tuning capacitor C_4 . Surprisingly, this proved to produce a material reduction of the oscillator oscillations transmitted
 50 to the antenna.

Preferably capacitor C_u should be connected to the inner conductor L_2 at a point nearer to an oscillator frequency antinode in the high-frequency part of the tuning range of the oscillator than to an oscillator frequency antinode in the low-frequency part of the tuning range of the oscillator. This ensures that compensation is produced at high frequencies, that is to say in the range in which reactive superposition of the oscillator oscillations is a maximum; thus a more even compensation is obtained. The described shifting of the antinodes is produced in known manner by variation of the tuning capacitor C_4 which is mechanically coupled with the tuning capacitors C_3 and C_6 .

65 What is claimed is:

1. An ultra-high frequency heterodyne receiver comprising first and second tank circuit chambers having centrally disposed inner conductors, a source of signal oscillations, means applying said signal oscillations to said first chamber, means for coupling said signal from said first chamber to said second chamber, a mixing device

having a control electrode, means providing local oscillations connected to said mixing device, means inductively coupling the signal oscillations in said second chamber to said control electrode, and means for substantially reducing oscillations of the frequency of said local oscillations at the input of said receiver comprising a capacitor connected between said control electrode and a potential antinode point on the inner conductor of said second chamber.

2. An ultra-high frequency heterodyne receiver comprising first and second tank circuit chambers having centrally disposed inner conductors, a source of signal oscillations, means applying said signal oscillations to the central conductor of said first chamber, means for coupling said signal from said first chamber to said second chamber, an electron discharge device having a cathode and a grid, means connecting said grid to the wall of said second chamber, means inductively coupling the signal oscillations in said second chamber to said cathode, means providing local oscillations connected to said discharge device, and means for substantially reducing oscillations of the frequency of said local oscillations at the input of said receiver comprising a capacitor connected between said cathode and a potential antinode point on the inner conductor of said second chamber.

3. An ultra-high frequency heterodyne receiver comprising first, second and third tunable tank circuit chambers having centrally disposed inner conductors, a source of signal oscillations, means applying said signal oscillations to the inner conductor of said first chamber, means

coupling said signal oscillations from said first chamber to said second chamber, an electron discharge device having cathode, grid, and anode electrodes, means connecting said grid electrode to the wall of said second chamber, means inductively coupling the signal oscillations in said second chamber to said cathode electrode, means connecting the inner conductor of said third chamber to said anode electrode whereby local oscillations are generated at a frequency determined by said third chamber, and means substantially compensating for oscillations of the frequency of said local oscillations at the input of said receiver comprising a capacitor connected between said cathode electrode and a potential antinode point on the inner conductor of said second chamber.

15 4. The receiver of claim 3 in which said means coupling said signal oscillations to said cathode electrode comprises a conductor loop extending parallel to the inner conductor of said second chamber.

20 5. The receiver of claim 3 comprising first, second and third ganged variable capacitors disposed in said first, second and third chambers respectively and connected between a wall and one end of the inner conductor of the respective chamber.
